Primary Examiner — Rhea Shields(74) *Attorney, Agent, or Firm* — Justin Lampel(57) **CLAIM**

The ornamental design for a retracting extension cord reel as shown and described.

DESCRIPTION

FIG. 1 is a perspective view of a retracting extension cord reel showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is an enlarged top plan view thereof;

FIG. 8 is an enlarged bottom plan view thereof;

FIG. 9 is a partial enlarged view of portion 9 in FIG. 1; and, FIG. 10 is a partial enlarged view of portion 10 in FIG. 1. The broken lines depict portions of the retracting extension cord reel and form no part of the claimed design.

The dot dash line is included for the purpose of illustrating the bounds of the enlarged view and forms no part of the claimed design.
